CLAIM

The ornamental design for a light fixture, as shown and described in the drawings.

DESCRIPTION

FIG. 1 is an upper side perspective view of a light fixture of the present invention;

FIG. 2 is a top plan view of a light fixture of the present invention;

FIG. 3 is a bottom plan view of a light fixture of the present invention;

FIG. 4 is a left side elevation view of a light fixture of the present invention;

FIG. 5 is a right side elevation view of a light fixture of the present invention;

FIG. 6 is a rear elevation view of a light fixture of the present invention; and,

FIG. 7 is a front elevation view of a light fixture of the present invention.

The broken lines shown are included for the purpose of illustration only and form no part of the claimed design.
